UNITED STATES PATENT OFFICE.

EDWARD G. SEIFFER, OF EVANSVILLE, INDIANA.

HOSE-SUPPORTER.

SPECIFICATION forming part of Letters Patent No. 680,503, dated August 13, 1901.

Application filed May 1, 1901. Serial No. 58,296. (No model.)

To all whom it may concern:

Be it known that I, EDWARD G. SEIFFER, a citizen of the United States, residing at Evansville, in the county of Vanderburg and State 5 of Indiana, have invented certain new and useful Improvements in Hose-Supporters, of which the following is a specification.

My invention relates to improvements in hose-supporters, and has particular reference 10 to improving the clasp or fastening; and one object of my invention is the provision of a clasp which can be easily applied and detached from the hose, which will insure a reliable fastening which cannot become accidentally detached, and which cannot possibly 15 injure the hose by wearing or tearing.

Another object of my invention is the provision of a hose or garment supporter which will be of simple, durable, and inexpensive 20 construction, which will be ornamental and attractive in appearance and small and compact in size, and thoroughly efficient for the intended purposes.

To attain the desired objects, my invention 25 consists of a hose-supporter embodying novel features of construction and combination of parts, substantially as disclosed herein.

Figure 1 represents a perspective view of my device applied in operative position, the 30 stocking being shown in dotted lines. Fig. 2 represents a perspective view of the clasp portion of my device. Fig. 3 represents a sectional view through the clasp, showing the manner of grasping the stocking.

35 In the drawings the letter A designates the usual elastic or web band, having at one end the hook B to receive the cord C, which cord passes through the other end of said band, and to the free end of the cord is secured the sleeve D, having the depending arms D', to which is secured the clasp, as will appear.

The clasp or fastener constitutes the main feature of my device and is of extremely 45 simple and practical construction and is composed of the lower member or plate E, having the upper cross-piece E', which is connected to the arms of the sleeve and at its lower end is formed with the head or enlargement 50 E², which carries the headed stud E³, and the

cross head or piece E' is formed with the hooks E⁴, which pass through eyes F in the cross-piece F' of the other member or plate F². This member F² is formed at its lower portion with a similar enlargement F³, provided with an opening, and in said opening is secured by the ring F⁴ the flexible or elastic piece F⁵, which is provided with an opening F⁶, the purpose of which is to receive and hold secure against accidental detachment the stud on the lower member. 55

From the foregoing description, taken in connection with the drawings, the manner of operating my device will be readily understood, and it will be seen that the lower member carries the stud which engages the stocking, and when the upper hinged member is forced down the stud forces the material of the stocking through the opening in the elastic piece and holds the stocking securely, 60 but without danger of tearing, as is frequently the case with the metal clasps; also, the clasp can be instantly applied and detached, and being of simple, inexpensive, and practical construction, as well as ornamental and small in size, it will readily commend itself. 65

While I have shown and described my improvements as applied to a hose or stocking supporter, I would have it understood that I 70 may use the improvements wherever they will perform their functions effectively, and I also reserve the right to make such changes in the device as come within the scope of my invention. 75

I claim—

1. The combination of a lower member having a stud, an upper member pivotally connected to the lower member and having a flexible or elastic keeper having an opening adapted to be expanded by and for engaging the stud and securing the hose or other material and a clamp secured upon the elastic keeper for holding the said elastic keeper. 80

2. The combination of a band, a cord connected to the band, a sleeve carried by the cord, and a clasp secured to the sleeve and composed of a lower member having a securing-stud, and an upper member hinged to the lower member and having an apertured flexible keeper. 85

ble keeper to receive and retain the stud and a clamp secured upon the elastic keeper for holding the said elastic keeper.

3. The combination of a lower member, a securing-stud carried by the lower member, an upper member hinged to said lower member and formed with an opening, an apertured keeper of flexible or elastic material above said opening, and a clamping-ring for holding the elastic keeper in place.

4. A hose-supporter, consisting of the band, the cord for engaging the band carrying a sleeve, the clasp having its lower member secured to the sleeve, said member having a stud, the upper member hinged to a cross-bar on the lower member and having a flexible apertured keeper to receive the stud on the lower member to secure the stocking.

5. The combination of the cross-piece having the hooks, the plate connected with the cross-piece and carrying the stud, the upper member having the cross-piece hinged to the hooks, the elastic piece carried by the hinged

member and having an opening to receive the stud, and the ring for securing the elastic piece. 25

6. The combination of the lower member carrying the securing-stud, the upper member having the opening covered by the elastic piece formed with an opening to receive the stud, and the ring around the outer edge of the opening in the upper member for securing the elastic piece. 30

7. The combination of the lower plate having a head or enlargement at its lower end carrying a stud, an upper plate having a similar enlargement formed with an opening, a flat elastic piece secured over and entirely surrounding the said opening and having a securing-opening to receive the stud. 35 40

In testimony whereof I affix my signature in presence of two witnesses.

EDWARD G. SEIFFER.
